AMMUNITION SHELL

Harry C. Luft, Spokane, Wash.

Application September 22, 1947, Serial No. 775,391

1 Claim. (Cl. 102—44)

1

My present invention relates to an improved ammunition shell and especially to the method and means employed in modifying such shells as may be lacking in the conventional end flange of the type normally used with firearms of foreign construction.

Many domestic shell's do not have the necessary flange extending beyond the cylinder of the shell and it is the object of my invention to afford a simple and inexpensive method and structure for modifying such shells and adding the flange so that such shells may be used in foreign firearms.

In the accompanying drawings I have illustrated one complete example of the physical embodiment of my invention according to the best mode I have thus far devised, but it will be understood that various changes and alterations may be made in the exemplified structure within the scope of the appended claim.

In the drawings:

Fig. 1 is an elevational view of a shell before modification.

Fig. 2 is a longitudinal sectional view therethrough, with the annular ring turned down slightly and the projectile receiving tube reduced in length.

Fig. 3 is a sectional view of the flange ring to be added.

Fig. 4 is a sectional view through a tapered die.

Fig. 5 is an elevational view of the shell showing the shrunken ring in position and in section.

Fig. 6 is a view of the modified shell.

Referring now to the drawings wherein I have illustrated the present preferred embodiment of my invention, I employ a cartridge casing having a central cylindrical wall 2 tapered slightly toward the projectile receiving end tube 4. The head of the cartridge is closed by wall 6 having an opening 8 for the detonation and the exterior of the head has an inwardly tapering or converging face 10 terminating against the annular ring 12 of approximately the same diameter as the maximum diameter of the wall 2.

In order to permit the use of such casings in domestic rifles using the rimmed cartridge and foreign firearms, the recess must be filled and an annular flange must be provided of greater diameter than that of the casing.

I therefore place the shell 2 in a lathe and reduce the diameter of the annular ring 12 to receive a ring 14 having an inner flange 16 adapted to fit into the recess of the casing, loosely.

The casing and ring is then pressed through the

2

die 18 having tapered inner wall 20 by plunger 22 moving in guide head 24.

During its passage through the die, the ring is shrunk onto the casing to fit snugly in the groove or recess of the casing and to snugly engage the ring 12.

The ring 14 may then be turned in a lathe so that a portion is removed to make the face 26 flush with the casing and wall 2 thereof, and to leave the flange ring 28 extending beyond the surface of the casing.

In many instances it will be necessary and/or desirable to reduce the length of the end 4 by cutting off a portion thereof, as shown.

By the use of the ring and the method of applying the same, domestic cartridges may be made usable in guns requiring a rim and after the modifying ring is pressed and shrunk onto the cartridge and turned on a lathe, the casing 10 may be charged and the projectile located in the tube 4.

Having thus fully described my invention what I claim as new and desire to secure by Letters Patent is:

25 An ammunition shell having a head formed with an annular tapered recess and an annular flange having a flat peripheral face of lesser diameter than the shell body and having a flat inner surface, and a ring on the shell having an interior tapered flange in the recess formed with a squared shoulder abutting the flat inner surface of the head flange, and an exterior annular flange of greater diameter than the shell casing and of substantially the same thickness as the 30 annular flange of the head.

HARRY C. LUFT.
